UNITED STATES PATENT OFFICE.

ADOLPH KLEIN, OF NEW YORK, N. Y.

COLLAPSIBLE TOY.

No. 908,777.

Specification of Letters Patent.

Patented Jan. 5, 1909.

Application filed March 14, 1908. Serial No. 421,086.

To all whom it may concern:

Be it known that I, ADOLPH KLEIN, a citizen of the United States of America, residing in the borough of Manhattan, city 5 and State of New York, United States of America, have invented a new and useful Improvement in Collapsible Toys, Toy Furniture, and the Like; and I do hereby declare the following to be a full, clear, and 10 exact description of the same.

The present improvements relate to collapsible and foldable toy-furniture, such as toy wardrobes, toy chiffonniers, toy dressers, toy-sideboards, toy and doll houses, etc., and 15 the object of the invention is to provide a simple, economical and durable toy which, when not in use, may be packed or folded so as to occupy very little space for storage or shipping, and which is a source of amusement and instruction to children in repeatedly building and assembling, or in collapsing and folding, the toy.

The drawings show a toy chiffonnier and a doll's house which belong, especially, to the 25 series of toys devised by me and called "Ta-Ka-Part" toys, and the parts thereof are usually composed of heavy and tough pasteboard.

Referring to the accompanying drawings, 30 Figure 1 is a perspective view of a chiffonnier, assembled, embodying my invention; Fig. 2 is a like view, enlarged, showing the parts of such chiffonnier in disconnected relation; Fig. 3 is a side view, showing the relation of the 35 chiffonnier parts when folded; Fig. 4 is a perspective view of a doll's house, assembled, embodying this invention; Fig. 5 is a perspective view of said house, with the front thrown open, to expose the interior—the 40 attic being broken away—and with the roof lifted therefrom; and Fig. 6 is a side view, showing the relation of the parts of the house, when folded.

The toys shown in the drawing, each consist 45 of a folding and collapsing frame—for instance, one having two opposite panels, constituting the sides of a toy chiffonnier or of a doll's house, both having a hinged connection with a panel constituting the back of 50 the toy.

As shown in the drawings, the frame has 55 opposite side panels, C and C² (Fig. 2) or C⁵ and C⁸ (Fig. 5), and the frame is also provided with a panel (C⁴ or C⁶) which is directly hinged along one edge—as shown in Fig. 2—to one side panel, and hinged, along its other

edge, to a leaf (C² Fig. 2, or C⁷ Fig. 5), which is, in turn, directly hinged to the other side panel. The frame is provided with a front panel or door (C⁴ or C⁶), which constitutes 60 the door of the piece of toy furniture or the front of the house.

The toy, whatever its construction, will have supports, E and E¹ (Fig. 2) or seats E⁵ and E⁶ (Fig. 5) secured to the inner faces of 65 the side panels. For this purpose, I prefer to use small wooden strips extending cross-wise of said panels. Each support carries a pin (e or e¹) projecting upwardly therefrom. Openings, c³, c⁴ are formed in the side panels 70 near their bottom edges, and (as shown in Fig. 2) are also sometimes formed in those panels near their upper edges. The frame, when folded, is in a position to support and to be held by a panel F (Fig. 2) which has, near 75 its ends, openings into which the pins e and e¹ are fitted, thus utilizing the panel F to hold the sides in stiff relation, while said panel rests upon the supports E and E¹. The panel F may represent a shelf in a chiffonnier, 80 and when a plurality of panels, as F² and J (Fig. 5), are used, they may represent successive floors of the doll's house. Each toy will also, preferably, comprise a base, a, 85 readily separable from and attachable to the frame when in open position. To assure this, each base may have cross-wise wooden strips, b and b¹ (Fig. 1) and b¹ and b² (Figs. 5 and 6) upon its upper face, each strip having pins (c¹ and c², Fig. 2) which fit the 90 openings, c³ and c⁴, along the bottom edge of the sides of the frame. To hold the sides of the frame into gripping relation with the strips of the base, a bottom panel (D, Fig. 2 or D¹ Fig. 5) representing the floor of the 95 house or of the chiffonnier—is closely fitted into the folded frame, as shown in Fig. 5, clamping the sides (C⁵ C⁸) of the frame against the strips and firmly seating the pins of the latter, as illustrated at c into the bottom 100 openings of the sides. The front of the frame is preferably provided with an eye (y, Fig. 1), which receives a hook z on the side of the frame.

To complete the toy, it may have a readily 105 removable top G (Figs. 1 and 2) provided with cross-wise bottom strips H and H¹ each having a pin, h or h¹, and said top may be secured in a manner similar to the connection of the bottom. Or, as shown, in Fig. 5, 110 the top may consist of two pieces of pasteboard (K¹, K²) hinged together, and having

side strips L and L¹, the whole representing a readily removable and attachable peaked roof for the doll's house. The base may have (see Figs. 1, 2 and 3) short legs or supports x and x¹. When folded, the new toy occupies very little space, as shown in Figs. 3 and 6. The compactness is, in a great measure, due to the leaf (C² or C⁷), which permits the panels C and C¹ to be folded down against the panels C³ and C⁴, notwithstanding the attachment of the wooden strips to the side-panels.

I claim:

- 15 1. In a toy, a folding and collapsible frame comprising connected front, rear and side panels, and each of the latter panels having openings along its bottom edge, in combination with a removable panel within said frame and holding it in the desired open position, a base removably connected with said frame when in the open position and having pins engaging in said openings along the bottom edges of the side panels, and with a top panel.
- 20 2. In a toy, a folding and collapsible frame comprising connected front, rear and side panels, and each of the latter panels having openings along its bottom edge and strips extending across said side panels above said openings and each provided with a pin, in combination with a removable panel within said frame and having openings for engagement by the pins aforesaid to hold the

frame in the desired open position, a base removably connected with said frame when in the open position and having pins engaging in the mentioned openings along the bottom edges of the side panels, and with a top panel.

3. In a toy, a folding and collapsible frame comprising connected front, rear and side panels, and each of the latter panels having openings along its bottom edge, in combination with a panel within said frame and holding it in the desired open position, a base removably connected with said frame when in the open position, and having widthwise-extending strips provided with pins engaging in said openings along the bottom edges of the side panels, and with a top panel.

4. In a toy, a folding and collapsible frame comprising a rear panel, a side panel having a hinged connection with the rear panel along one of its side edges, a leaf having a hinged connection with said rear panel along the other of its side edges, and a side panel having a hinged connection with the aforesaid leaf.

In testimony whereof, I have signed my name to this specification in the presence of two subscribing witnesses.

ADOLPH KLEIN.
